UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

OIL-HEATING FURNACE.

Application filed January 28, 1922. Serial No. 532,482.

To all whom it may concern:

Be it known that I, JOHN E. BELL, a citizen of the United States, residing at Brooklyn, in the county of Kings and State 5 of New York, have invented certain new and useful Improvements in Oil-Heating Furnaces, of which the following is a specification.

My invention relates more particularly to 10 pressure stills used for the purpose of cracking hydrocarbons of higher boiling points such as crude petroleum, gas oil and the like, to form more volatile or lighter hydrocarbons such as those that constitute commercial gasoline and has specifically for its 15 object to protect the tubes from overheating or burning and to lengthen the time of the runs between cleaning with a corresponding increase in the distillate produced.

20 Stills for cracking oil are heated by furnaces in which coal, gas or oil is burned and for economy in fuel consumption it is desirable that the fuel be burned in the furnace with the least amount of excess air and 25 the maximum furnace temperature. When there is a fresh charge of oil in the stills free from carbon this can be done without fear of injury to the tubes or other heat absorbing portions of the still. When, how-

30 ever, carbon is formed in the process and is deposited on the inside of the tubes or heating elements of the still as in the case of cracking stills, this condition no longer exists as the coating of carbon or heavy tar 35 is a poor conductor of heat and insulates the metal surface from the oil on the inside with the results that the temperature of the metal increases over the temperature of the oil, the amount of this increase being pro-

40 portional to the thickness of the carbon deposit and to the amount of heat delivered to the external surface heated from the furnace. It follows that unless stills are frequently shut down for cleaning or the tem- 45 perature of the furnace itself is reduced it is difficult to maintain the stills in opera-

50 tion for a sufficient length of time to make such operation commercially practical. There is also a hazard to life and property 55 due to the possible bursting of a tube which has become overheated and burnt, as the pressure in the stills is maintained at approximately 100 pounds per square inch and any break or rupture is followed by disastrous fire. The tubes or other heating sur-

faces most exposed to the heat of the furnace will be the first to suffer and it is the object of my invention to reduce the amount of heat absorbed by these tubes or surfaces and increase the amount of heat absorbed by 60 the other portion of the still without sacrificing either fuel economy or capacity of the still.

It is well known that with the ordinary arrangement of furnace such as used for 65 heating boilers and heretofore used under stills a large proportion of the heat in the fuel passes directly from the fuel-bed, where solid fuel is used, or from the flame and hotter brick work when gaseous or oil fuel 70 is used, direct to the heat absorbing surface of the boiler or still by radiation and it has been shown by tests that the amount of heat absorbed by the tubes next to the fire in a boiler may be and usually is forty or fifty 75 times as great as the average absorption of heat throughout the whole surface, and this amount of heat is principally transferred as radiant energy. It has also been shown that heat transferred in this way increases very 80 rapidly with the furnace temperature; the process in general being controlled by Stefan's law for radiation which makes the total amount of radiation proportional to the fourth power of the absolute tempera- 85 ture of the radiant. When the furnace is arranged so that the direct radiations are shielded from the heat absorbing surfaces, such shields and the gas connecting passages become secondary radiators and the total 90 amount of heat transmitted in this way is greatly reduced. The heat that otherwise would be transmitted by radiation is absorbed by the gases with the result that there is an actual increase in gas tempera- 95 ture entering the cooling surface of the boiler or still, but this increase in gas temperature does not compensate for the reduction in the radiant heat so that as a net result the surface of first contact would not 100 absorb as much heat.

In my improved form of still the heat absorbing surface is protected from the direct radiation of the furnace by the inter- 105 position of a high bridge wall and a vertical flue with refractory walls, in its preferred arrangement, although other forms of passages and screens might be used. To still further protect the still surface of first contact with the furnace gases, I introduce a 110

diluting body of air or gas into the connecting flue, at a point near the furnace. This reduces the gas temperature and also the temperature of the refractory walls. The 5 heat absorbed by the surface first in contact with the furnace gases is thus reduced in two ways; namely, by the lower temperature of the gas and second, by a reduction in the temperature of the refractory second-
10 ary radiating surfaces. If the diluting gas is not heated, the obvious result is a reduction in efficiency such as accompanies the burning of fuel with an excessive amount of air. I have found, however, by experi-
15 ment that if the temperature of the dilut- ing gas is approximately the temperature of the waste gases leaving the still surface that not only is there no reduction in the fuel economy and capacity but on
20 the other hand there is a slight increase in both.

I may use either one of two methods for supplying the dilutant gas at the proper temperature. In one way of applying this 25 invention a proportion of the waste gas at the temperature at which it leaves the still is drawn aside and returned to the furnace. The other way is to install an air-heater in the flue leading from the still and to force 30 through this heater the air that is used as a diluting medium thus heating it to the proper temperature before forcing it into the flue between the furnace and still. Re-
35 ferring to the first method it is obvious that when the same amount of fuel is burned in the furnace that a measure of efficiency and capacity of the still can be made from the temperature and weight of the waste gases. The weight of the gases is not, however, 40 changed in my improved heater and experience and theory show that this tempera-
ture is reduced. In a still in which oil is mechanically circulated the temperature of the heat absorbing surface differs little from 45 that of the oil which for the purpose of calculation can be considered as uniform. The heat transfer equations show that the difference in temperature between the waste gases and the oil is proportional to the differ-
50 ence in temperature between the furnace gases entering the heater and the oil, and to a factor in which the ratio between the heat transfer rate and the gas weight appears. Tests have shown that the heat transfer rate 55 and the gas weight is in turn proportional to the gas flow or with a fixed surface, to the gas weight and as a consequence this ratio and the second factor are practically unchanged when this device is used. It, 60 therefore, follows that for the same heat absorption the exit temperature of the gases will be reduced as the inlet temperature is reduced and this, as has been pointed out above, has proven true in practice.

When air is used for the dilutant fluid

it is practical to bring this air, by the use of a waste gas heater, to approximately the temperature of the gases leaving the still. When this is done the argument just made applies and the efficiency and capacity of the still is slightly increased. When the air-heater is smaller and the temperature of the air is not raised to this point there may be a slight reduction in the efficiency and capacity. In view of this fact and in 75 view further of the fact that with the first method the air-heater is eliminated I prefer returning a portion of the waste gases to the furnace, but it is entirely possible that conditions would arise which would make it 80 desirable to use the air-heater method so that, in the more comprehensive claims, I claim both methods in combination with the flue passage as within my invention.

Increasing the gas flow over the heating surface by the use of either arrangement increases the friction loss and to maintain the same furnace draft it is necessary to have an increased draft at the still outlet. When this is provided for not only will the capacity of the still be maintained when this device is in use, but the efficiency will be slightly increased and on account of the lower temperature of the gases striking the first tubes of the heater the tubes will be 95 protected.

The invention in its broader aspects is independent of the particular form of still system with which the heating device is used. As an instance of an oil still in which it may be employed to particular advantage reference may be made to Patent No. 1,285,-
200 granted to the Sinclair Refining Company, November 19, 1918, on the application 100 of Edward W. Isom. In the accompanying drawings I have shown a preferred form of my invention in which the gases coming from the fire-box are tempered by an admixture of products of combustion which have been more or less cooled by circulation 105 through the heating chamber in contact with the oil tubes therein, and also an example of a somewhat similar furnace in which the gases are tempered by an admixture of air preheated by means of the waste gases from the furnace. It is to be understood, however, that these specific disclosures are for the purpose of exemplification only and that the scope of the invention is defined in the following claims, in which I have endeavored to distinguish it from the prior art so far as known to me, without, however, relinquishing or abandoning any portion or feature thereof.

Figure 1 shows in longitudinal, vertical section a furnace embodying that form of my invention in which the gases from the fire box are tempered by the return of a portion of the spent gases; Fig. 2 is a similar view of a somewhat different type of oil 125 130

heating furnace in which the gases from the fire-box are tempered by means of pre-heated air, Fig. 3 is a transverse, vertical section of the same on the line 3—3 of Fig. 2; Fig. 5 4 a horizontal section on the line 4—4 of Fig. 2, and Fig. 5 a fragmentary sectional view on the vertical plane of line 5—5 of Fig. 4.

Referring to the form of the invention shown in Fig. 1 of the drawing, the furnace comprises a fire-box 1 which may be of any usual or preferred form, communicating by an elongated throat 2 with the heating flue or chamber 3 containing the oil heating tubes. The chamber 3 is of considerable vertical length and communicates at its lower end with a stack flue 4. I have shown the fire-box as equipped at 5 with a mechanical stoker and at 5^a with burners, by means of which oil or gas may be used as a fuel. The elongated throat 2 is separated from the heating flue or chamber 3 by a lengthy bridge-wall 6 which overhangs at its top as at 30 into the throat of the fire-box. The purpose of the elongated throat and overhanging bridge-wall is to shield the tubes in the heating flue from direct radiation from the fire-box.

The battery of heating tubes 7 is connected at top and bottom to headers 9, 12, respectively, both of which headers are outside the heating flue. The tubes 7 extend through an opening 8 in the top wall of the furnace, which is closed by a perforated slab 8^a of refractory material through which the tubes extend. At their lower ends the tubes 7 extend through a slab of refractory material 10 beneath which the header 12 is located. The slabs of refractory material rest upon collars formed on the tubes as shown in the view, and the lower plate or slab 10 rests upon angle irons 13 at its edges. The entire battery of tubes is sustained from the top header so as to be free to expand and contract with change of temperature. The top header is supported upon I-beam 9^a on top of the furnace. The lower header is connected to a manifold 12^a which receives oil through the pipe 12^b. The upper header is connected to a manifold 9^b, which in turn connects with a pipe or pipes 11. The oil received through pipe 12^b enters the header, flows upward through the bank of tubes to the upper header and thence through the manifold and pipe 11. When the heater is employed in a system of the type shown in the Isom patent to which reference has been made, the pipes 11, 12^b are connected to the bulk supply tank, such as shown at C in the patent and preferably one or both of them are provided with means for accelerating the circulation as shown in said patent. The heating flue is provided with baffles 14, 15 which cause the hot gases to pass back and forth among the tubes of the battery a number of times,

reaching the stack flue 4, by which they make their exit.

By reason of this thorough circulation among, and contact with the oil heating tubes, the heat is efficiently extracted from the products of combustion before they reach the stack flue, and the efficiency of the device is further increased due to the fact that the general direction of flow of the heating gases and oil is opposed so that the relatively cool oil entering at the bottom of the tubes extracts the heat from the partially cooled gases and its temperature increases until it is at the maximum in the upper pass of the furnace where it is exposed to the gases fresh from the fire-box. As heretofore observed, however, the oil heating tubes are screened from direct radiation from the fire-box, even at their upper ends, thus preventing overheating with the consequences to which reference has heretofore been made.

In order to further reduce the temperature of the hot products of combustion, coming from the fire-box before they strike the oil containing tubes, I provide, in the form of my invention shown in Fig. 1, means for returning a portion of the partially cooled gases from the exit end of the heating chamber and mixing it with the fresh products of combustion from the fire-box. For this purpose I provide a return flue or flues 16 on one or both sides of the furnace, which connect with the lower end of the heating chamber at 17 and with a transverse flue or boxing 18 extending across the throat of the fire-box. This boxing is formed with a longitudinal opening or openings 19, communicating with the throat of the furnace. A forcing means of any desired or well-known character is interposed in each of the flues 16. In the exemplification of the invention shown in Fig. 1 I have shown a common venturi construction at 20, for this purpose. By suitably controlling the forcing means any desired proportion of the products of combustion may be returned to and intermingled with the hot gases rising from the fire-box. By this means, as above pointed out, I am enabled to temper the hot gases to any point desired, preventing overheating of the tubes at the upper pass and particularly the front tubes thereof, without reducing the thermal efficiency of the furnace, as pointed out in the opening paragraphs of the specification. By thus returning a portion of the products of combustion the volume of gases in contact with the tubes and consequently the rapidity of flow is increased and, therefore, the heating effect is improved and at the same time the heat is more evenly distributed throughout the tubes and throughout the length thereof.

In the embodiment of the invention illustrated in Figs. 2 to 5 inclusive, as above

stated, instead of mixing cool products of combustion with the hot gases from the firebox arrangements are made for preheating a volume of air by the waste gases and mixing the air so preheated with the gases from the fire-box. I have shown this form of the invention as applied to a somewhat different form of heating furnace in which the oil tubes instead of being vertical are horizontal but it will be obvious that this means of tempering the hot products of combustion could be employed in a furnace which is otherwise like that shown in Fig. 1.

In this second embodiment of the invention illustrated in Figs. 2 to 5 inclusive, the general arrangement of the furnace including the firebox 1^a, elongated vertical throat 2^a and downwardly extending heating flue 3^a with baffles 14^a and 15^a is substantially like the furnace heretofore described. The oil heating tubes 7^a, however, are arranged horizontally in the heating flue and connect series of headers 36, 36^a, etc., 37, 37^a, etc., arranged respectively in openings 38 and 39 formed in opposite side walls of the heating flue. The openings are closed outside the headers by doors 41 of suitable material. The lowermost header on the left-hand side of the furnace, as seen in Fig. 3 is provided with a connection 42 to serve as an inlet for the oil, and the upper header is provided with a similar connection 43 to serve as an outlet for the oil. It will be noted that the uppermost and lowermost headers on the left-hand side of the furnace, in other words those to which the inlet and outlet are respectively connected, receive only two horizontal rows of pipes whereas the intermediate headers on the same side and all of the headers on the other side of the furnace receive four horizontal rows of pipes. This provides for a continuous circulation of the oil received through the inlet 42 back and forth across the heating chamber in its passage to the outlet 43 so that it is exposed many times in its passage through the furnace to the heat of the products of combustion circulating about said pipe in its zig-zag passage from the top to the bottom of the heating flue.

In the form of the invention now under consideration the stack flue 4^a communicates with a vertical flue 40 which, at its upper end connects with a horizontal flue 31 leading to the stack. A battery of vertical tubes 32 is arranged in this vertical flue and communicates at its upper end with a boxing or flue 33 through which the pipes are supplied with air. The lower end of the tubes communicate through a header 35 with a horizontal flue 34 leading to an outlet 34^a in front of the bridge wall. The spent gases from the bottom of the heating chamber pass up the vertical flue 40 and heat the flue 32 therein. The air entering the flue

33 flows counter-current to the gases down the pipes 32 and into the flue 34 along which it flows to the outlet 34^a where it intermingles with and tempers the hot products of combustion from the firebox. Obviously, in this form of oil heating furnace, instead of preheating air in this manner and discharging it into the firebox a portion of the cooled products of combustion from the lower end of the heating chamber 75 might be returned to the firebox, as in the previously-described form of the invention.

In both forms of the invention as heretofore pointed out, I provide for returning the hot gases to the firebox and shielding 80 the tubes from direct radiation, and furthermore I cause the oil to flow countercurrent to the products of combustion whereby, as pointed out in the opening paragraph of the specification, the heat absorption is distributed as evenly as possible throughout the oil heating element and overheating of any portion thereof is prevented.

I claim:

1. A tubular oil cracking still having a 90 heating chamber, a series of oil heating tubes adapted to be externally heated extending therethrough, a fire box communicating with one end of said heating chamber, a flue communicating with the other end of 95 said heating chamber, and means connecting said heating chamber near the flue end thereof with the fire box for returning a portion of the heating gases from the heating chamber to the fire box, whereby the heating 100 gases from the fire box are tempered by the returned hot gases of lower temperature and the resulting mixture is passed through the heating chamber.

2. An oil cracking still having a heating 105 chamber, oil heating surfaces adapted to be externally heated therein, an inlet and an outlet to the heating chamber, a fire box communicating with the heating chamber at the inlet, a flue communicating with the outlet of the heating chamber, a flue connecting the heating chamber near the outlet with the fire box, and means for causing a return of a portion of the products of combustion 110 from the heating chamber through said flue to the fire box, whereby the heating gases from the fire are tempered by the returned hot gases of lower temperature and the resulting mixture is passed through the heating chamber.

3. A tubular oil cracking still having a heating chamber, an inlet and an outlet to the heating chamber, a fire box communicating with said chamber at the inlet thereof, a flue communicating with said chamber 115 near the outlet thereof, a series of oil heating tubes adapted to be externally heated extending through said heating chamber, a flue connecting the said heating chamber near its outlet with the fire box, and means 120

125

130

for forcing the return of a portion of the products of combustion from the heating chamber through said flue to the fire box, whereby the heating gases from the fire box are tempered by the returned hot gases of lower temperature and the resulting mixture is passed through the heating chamber.

4. A tubular oil cracking still having a heating chamber, a series of oil heating tubes adapted to be externally heated extending through said chamber, a fire box adjacent said chamber and communicating therewith at its upper end, an elongated bridge wall preventing direct radiation from the fire box against said tubes, a flue connected to the lower end of said heating chamber, and means for returning part of the heated gases from near the lower end of the heating chamber and introducing them to mix with the heating gases from the fire box, whereby the heating gases are tempered by the returned hot gases of lower temperature and the resulting mixture is passed through the heating chamber.

5. A tubular oil cracking still having a heating chamber, a series of vertical oil heating tubes adapted to be externally heated extending through said heating chamber, a flue communicating with the lower end of said heating chamber, a fire box having an elongated vertical throat communicating at its upper end with said heating chamber, a flue connecting the lower end of the heating chamber with the lower end of the throat, and means in said flue for forcing the return of partially cooled but still hot gases to the fire box, whereby the heating gases from the fire box are tempered by the returned hot gases of lower temperature and the resulting mixture is passed through the heating chamber.

6. A tubular oil cracking still having a heating chamber, a series of oil heating tubes adapted to be externally heated extending vertically therethrough, means on top of said chamber for supporting the heating tubes, a flue communicating with the lower end of the heating chamber, a fire box communicating with the upper end of the heating chamber, baffle plates in the heating chamber for causing the products of combustion to pass backward and forward over said heating tubes, and means for returning a portion of the products of combustion from near the bottom of the heating chamber to the fire box whereby the heating gases from the fire box are tempered by the returned hot gases of lower temperature and the resulting mixture is passed through the heating chamber.

7. A tubular oil cracking still having a fire box, a heating chamber communicating with the fire box, a flue communicating with the heating chamber, a battery of oil heat-

ing tubes adapted to be externally heated extending through the heating chamber, and means for supplying and for mixing a hot diluent of lower temperature with the hot products of combustion from the fire box, whereby the heating gases from the fire box are tempered by admixture with the hot diluent and the resulting mixture is passed through the heating chamber.

8. An oil cracking still having a heating chamber, oil heating surfaces adapted to be externally heated therein, a fire box communicating with the heating chamber at one end, a flue communicating with the heating chamber at the other end, and means for diluting the products of combustion from the fire box with hot gases at a lower temperature than the gases from the fire box whereby the products of combustion are tempered and diluted before they are passed through the heating chamber.

9. An oil cracking still having a heating chamber, oil heating surfaces adapted to be externally heated therein, a fire box communicating with the said chamber at one end, a flue communicating with the chamber at the other end, and means for tempering the hot products of combustion from the fire box by the introduction thereinto of hot gases from the heating chamber whereby the heating gases from the fire box are tempered by the returned heated gases and the resulting mixture is passed through the heating chamber.

10. An oil cracking still having a heating chamber with oil heating surfaces adapted to be externally heated therein, a fire box communicating with said chamber, and means for diluting the hot products of combustion from the fire box, at a point between the fire box and the heating chamber, with gas at a temperature approximately equal to that of the exit gases from said heating chamber.

11. A tubular oil still having a heating chamber with oil heating tubes adapted to be externally heated therein, a fire box communicating with said chamber, means for preventing direct radiation from the fire box against the tubes, and means for diluting the hot products of combustion from said fire box with heated gas at a lower temperature, at a point between the fire box and the heating chamber.

12. An oil cracking still having a heating chamber with oil heating surfaces adapted to be externally heated therein, a fire box communicating with said chamber, means for preventing direct radiation from the fire box against the oil heating surfaces, and means for diluting the hot products of combustion from the fire box with heated gas returned from the gases leaving the heating chamber at a point between the fire box and the heating chamber.

13. A tubular oil cracking still having a heating chamber with oil heating tubes adapted to be externally heated therein, a fire box communicating with said heating chamber, means for returning a part of the hot waste heating gases from near the outlet of the heating chamber and admixing them with the products of combustion from the fire box at a point between the fire box and the heating chamber, and means for circulating the admixed gases through the heating chamber generally counter current to the circulation of oil through the heating tubes.

14. A tubular oil cracking still having a

heating chamber with oil heating tubes adapted to be externally heated therein, and with baffles for causing the heating gases to pass therethrough in a series of passes and in a generally downward direction, a furnace chamber communicating with the heating chamber near the upper end and a stack near the lower end, and means for returning a part of the cooler gases from near the outlet of the heating chamber and admixing them with the products of combustion from the furnace chamber prior to entry into the heating chamber.

JOHN E. BELL.
